United States Patent Office.

JACOB KINZER, OF PITTSBURG, PENNSYLVANIA.

Letters Patent No. 80,974, dated August 11, 1868.

IMPROVEMENT IN REVERSIBLE LATCHES.

The Schedule referred to in these Letters Patent and making part of the same.

TO ALL WHOM IT MAY CONCERN:

Be it known that I, JACOB KINZER, of the city of Pittsburg, in the county of Allegheny, and State of Pennsylvania, have invented a new and useful Method of Constructing Reversible Locks; and I hereby declare the following to be a full, clear, and exact description thereof, reference being had to the accompanying drawings, making a part of this specification, in which—

Figure 1 is a perspective of the lock with the entire plate removed.

Figure 2, a face view of the same complete.

Figure 3, a face view with the upper portion of the plate taken off, showing the arrangement of the latch-bolt and follower; and

Figure 4 the same as fig. 3, with the latch-bolt removed.

Like letters refer to the same parts in the different drawings.

The manufacture of locks is so well understood that I need only describe such parts of this lock as differ from those now in ordinary use, and have some bearing on my invention. Nearly all varieties of locks are now made with one of the slides or plates of the case attached, and removable by the use of one or more screws; and locks are made reversible by having the latch-bolt so arranged that when the plate is removed, the bolt can be turned with its bevel to either side, as may be desired, but in so doing, all the springs and bolts inside the lock are left exposed and loose, as seen in fig. 1, and are liable to fly out and be lost, and so much trouble and confusion are thereby caused in taking out and reversing the latch-bolt, that locks so constructed have never gone into general use.

The object of my invention is to provide a lock which may be adapted to doors opening either to the right hand or the left, by simply reversing the latch-bolt C, without exposing or displacing any other of the inside works of the lock.

For this purpose, I divide the plate A in two parts, *a* *b*, the lower one of which, *b*, is made to extend over and cover the lock-bolt and its springs, the slide-bolt (if one is used) and its springs, and the spring B, which operates the latch-bolt C. This portion of the plate is held in its place by the screw F. The upper portion *a* of the plate A is properly fitted to the line or upper edge of the part *b*, and is made to cover the latch-bolt C and its follower D only. It is fastened to the case by the screw E, and may be removed at pleasure by simply taking out the screw. The spring B which operates the latch-bolt C, is made of suitable material and shape, and is bent or coiled around the lug or projection *c*, which I form on the inside of the case, and below the upper line of the lower part of the plate A. At a suitable distance above, and to the right of this lug *c*, I form another lug or projection *d*, for the spring B to rest against, and be retained in its proper position when the latch-bolt C is taken out to be reversed. The latch-bolt C and its follower D may be made according to any suitable and well-known plan.

The lock being thus constructed and put together, when it is desired to reverse its action, all the labor that is required is to take off the upper part *a* of the plate A, turn the latch-bolt C and its follower D to the proper side, as seen in figs. 3 and 4, and replace the plate *a*, the spring B being kept in its place by the arrangement of it described, as well as the other works of the lock, no parts of which, except those that require changing, being at all exposed or disturbed. This method of making locks reversible, is equally applicable to case-locks, or to locks which are fitted to the side of the door, and to mortise-locks or locks, which are set into the edge of the door.

Having thus described the nature and use of my invention, what I claim as new, and desire to secure by Letters Patent, is—

Constructing the plate A of a reversible lock in two pieces, in the manner shown and described, and operating in combination with the latch-bolt C and spring B, which latter is confined in the lower part of the casing of the lock, in the manner shown and for the purpose set forth.

JACOB KINZER.
